UNITED STATES PATENT OFFICE

LOUIS MARTIN, OF NEW LONDON, CONNECTICUT

KEYHOLE ILLUMINATING MEANS

Application filed August 30, 1929. Serial No. 389,572.

The object of this invention is to provide an illuminating device especially adapted for use on the doors of motor cars, whereby the keyhole may be illuminated upon pressure being exerted on the knob or handle.

A further object is to provide a handle for a door of the kind indicated, or of any other character, adapted to be similarly operated, this handle being carried by a spring held shank, so mounted that contacts are closed for an electric circuit thru a lamp mounted within a tubular element, when pressure is applied to the handle.

With the foregoing and other objects in view, the invention consists in the novel construction and arrangement of elements disclosed, it being understood that modifications may be made within the scope of the claim without departing from the spirit of the invention.

In the drawings forming part of this application:—

Figure 1 is a view of the device in section, as applied to the door of a motor car or the like.

Figure 2 constitutes a section thru the structure of the door, perpendicularly of the section of Figure 1, with the movable handle in elevation, and the mounting means for the handle.

Figure 3 is a transverse section on line 3—3 of Figure 1.

Figure 4 is a section thru a portion of the door and the adjacent body portion of the car, showing the completion of a circuit thru the door jamb and the door per se.

A fragmentary portion of the door of a motor car is designated 10, a portion of the body structure is designated 11, and a battery, or other source of current is shown conventionally at 12. One of the wires 13 from the battery is connected with contact pin or the like 14, and is adapted to engage contact 15 mounted on the door, at the lower edge thereof. Elements 14 and 15 may be supported within rubber blocks or the like such as that shown at 16. The other wire 17 of the battery is grounded at 18.

The latch spindle 20 has a cam or the like 21 adapted to operate latch 21', and the

spindle is carried by tubular element 22 adapted to receive the slideable shank 23 rigidly carried by handle 24.

The handle serves the usual purpose of a door knob or door handle, but in this instance it is slideable longitudinally within tube 22, within limits determined by stop or pin 25 operating in slot 26 in element 22.

A spring 27 surrounds the reduced portion 28 of element 22, and the end portion 29 is connected or formed with element 20.

Tube 22 is provided with an opening 22' thru which the rays of lamp 30 are directed toward a keyhole not shown. The element 22 is mounted within the face plate 33 secured at 34, and is held within said plate by spring 27 bearing against stop 27'.

Lamp 30 is mounted within socket 36, and the socket carries a contact element 37 cooperating with stationary contact 38 connected with lead wire 13'. The other contact for the lamp, or the central contact, is designated 38' and cooperates with pin or screw 39 in the reduced end 40 of shank 23.

A ground for the circuit is thus effected, and it will be noted that spring 42 abuts one end of element 23 and surrounds the reduced portion 40, and also abuts stop 44, so that the handle 24 is normally in an outer position, but upon pressure moves inwardly and closes the circuit at 37—38, thus energizing lamp 30, and providing illumination thru opening 22' for enabling the user to immediately determine the exact position of the keyhole of the latch or lock.

What is claimed is:—

A keyhole illuminating means including a door latch operating shank confined in a door, a tubular member having one end formed on the shank and extending outwardly of the door, said member provided with a reduced portion and an opening arranged over the keyhole of the door, a plate mounted on the reduced portion and secured to the door to limit the movement of the tubular member toward the door, a shoulder on the reduced portion, a spring between said shoulder and plate to maintain the tubular member and shank in proper position relative to the door and the latch thereof, a

slidable shank in the tubular member, a handle on the slideable shank for permitting the rotation of the tubular member by a person for actuating the door latch and to move the slideable shank relative to the tubular member, an electric lamp carried by the slideable shank and positioned adjacent the opening, contacts associated with the lamp and tubular member and electrically connected to an electrical source to illuminate the lamp when the slideable shank is moved inwardly relative to the tubular member, a stop in the tubular member, and a tension means between said stop and slideable shank to urge the latter in one direction to disconnect the contacts.

In testimony whereof I affix my signature.
LOUIS MARTIN.
